UNITED STATES PATENT OFFICE

CECIL E. BOYD, OF DETROIT, MICHIGAN, ASSIGNEE TO THE MURRAY CORPORATION
OF AMERICA, A CORPORATION OF DELAWARE

WORK GUIDE FOR SEWING MACHINES

Application filed August 8, 1931. Serial No. 555,962.

- My invention relates to improvements in sewing machines and more particularly to means for guiding the work to the needle when forming plaits or piping.
- 5 In preparing upholstery for use in automobile body interiors for example, such as seats, seat backs and for any other upholstery purposes, it is the practice to form parallel rows of plaiting in the outer finishing upholstery material which may be of mohair, velour, linen, or other suitable fabric. This outer covering is sewed to a suitable backing material which is generally a plain muslin fabric, in a certain manner to 10 form plaits. The finishing or outer upholstery material is generally stitched to this heavy backing material in any well known manner such as piping to form elongated pockets to receive cotton batten or other suitable filler material which is stuffed in the pockets between the backing and finishing material, which pockets are formed by plaiting the outer upholstery material as it is sewed to the backing.
- 15 It is an object of my invention to provide an improved device to guide the work in forming plaits in such upholstering and joining the backing material to the upholstery material in exactly parallel lines and forming plaited pockets of exactly equal size. The device of 55 my invention insures a mechanically accurate and positive guiding of the work and is of great advantage when the plaited pockets are narrow due to the positive guiding of the work by my device which eliminates, to 60 a great extent, the care required by the operator in stitching the pieces together and eliminates inaccuracies in the operation to more rapidly produce a better product.
- 20 It is an object of my invention to provide an improved device for use in plaiting upholstery.
- 25 It is another object of my invention to provide a positive guide for the work stitched on a sewing machine to facilitate accurate forming of pleated pockets in upholstery of predetermined equal size.
- 30 It is another object of my invention to provide an improved means for handling the work in attaching backing material to 70 the outer finishing material when plaiting upholstery.
- 35 It is a further object of my invention to provide a guiding device for positively forming parallel plaits when stitching finishing upholstery material to a backing strip.
- 40 A still further object of my invention is to provide an improved device for guiding material being worked upon when forming 85 plaited fabric, definitely determining the width of the plaits, which device may be readily attached to any type of sewing machine or sewing machine work table.
- 45 Other objects and advantages will become 90 apparent throughout a reading of the following detailed description and accompanying drawing in which
- 50 Figure 1 is a plan view of the device of my invention shown attached to the top of 95 a sewing machine table.
- 55 Figure 2 is an enlarged end view of the device of my invention taken on the line 2-2 of Figure 1.
- 60 Figure 3 is an enlarged fragmentary cross 100

sectional view taken on the line 3—3 of Figure 1.

Figure 4 is an enlarged cross sectional view taken on the line 4—4 of Figure 1 indicating the manner in which the material being worked upon is positioned in my guide device, and

Figure 5 is a fragmentary perspective view of a strip of the upholstery showing 10 the manner in which it is attached to the backing to form plaited pockets.

Referring now to the drawing in detail in which like numerals designate like parts throughout the several views, I have illustrated in Figure 1 a sewing machine or other work table 7 which is arcuately cut out at 8 to form a recess in which the operator sits. At the right hand side of the figure I have illustrated a sewing machine head 9 of any 15 well known conventional type which carries a stitching needle 10. The above described sewing table or work bench and sewing machine are of conventional type and well known in the art.

20 The work guiding device of my invention is shown associated with the table 7 and includes a supporting cross bar 11 which extends across the top of the table as illustrated in Figure 1 and is supported at each 25 of its ends in any suitable manner such as attaching to the table or the floor, this supporting means is not shown in the drawing. The cross bar 11 is supported above the top of the table 7 a suitable distance to allow the 30 plaited upholstery material or finished work to pass therebeneath as will be hereinafter described.

35 A lid 12 is hinged to the cross bar 11 as illustrated in Figures 1 and 2 of the drawing 40 by suitable hinges 13 and the lid 12 is offset at 14 as best shown in Figures 2 and 4 for a purpose which will hereinafter be described. It will be noted, however, that the lid 12 lifts upwardly as illustrated in the 45 dotted lines in Figure 2 and when dropped down, the offset portion 14 engages one side edge of the bar 11 which acts as a stop to maintain the lid in horizontal position over the work.

50 A horizontally disposed plate 16 which is of rectangular shape is disposed below the lid 12 and supported above the top of the table 7 in a suitable manner to clear the top 55 of the table a sufficient distance to allow a strip of fabric to pass therebeneath. The plate 16 is supported by the sewing machine head 9 by an angle iron bracket 17 secured to the plate 16 by suitable screws. The upwardly extending side of the angular bracket 17 is secured to an arm 18 which is carried by the sewing machine, by suitable screws or other fastening devices. It will be 60 understood that the plate 16 may be supported above the table top in any other de-

sired suitable manner, the form I have shown in the drawing being preferable.

An elongated angularly shaped guide member 20 is fastened to the top of the plate 16 by suitable screws or other fastening devices and extends lengthwise of the plate 16 exactly parallel to the forward edge of the lid 12 and in close proximity thereto when the lid is lowered, the guide 20 extending from one edge of the plate 16 to the other 70 as shown in the drawing. The device of my invention is so positioned relative to the needle 10 of the sewing machine head 9 that the needle 10 will be reciprocated at a point a slight distance inwardly of the forward 75 edge of the lid 12 which distance is equal to the width of the piping or stitched seam to be sewed in the material. The material is passed from the left hand side of the work table 7 toward the right hand side and fed 80 directly to the needle 10 as shown in Figure 3.

I have illustrated in Figure 5 one form 85 of plaited upholstery which may be formed with the improved device of my invention. 90 In this figure is shown a strip of backing material 22 of muslin or any other suitable material having a piece of finishing upholstery material 23 such as velour for example, having elongated parallel plaits formed by 95 stitching the finishing upholstery material to the backing at 24 by folding back the outer finishing material 23 and piping it along this line.

100 As shown in Figure 4, the work is passed through the device of my invention by sliding the backing strip of muslin 22 on the surface of the work table 7 underneath the plate 16 and by passing the finishing velour over the plate 16 and folding it back over 105 the lid 23. As the material is passed to the right toward the needle 10 the backing muslin 22 and upholstery velour 23 will meet at the right hand edge of the lid 12 and plate 16 which terminate at the sewing machine head 9 in close proximity to the needle 10 thereof. The upholstery velour 23 will be stitched to the backing 22 at this point in 110 a seam known as piping.

115 It will be noted in Figures 2 and 4 that a groove 25 is formed along the lower rear longitudinal edge of the plate 16 and extends entirely across the plate exactly parallel to the forward edge of the lid 12 and to the guide 20. A tongue 26 is thus formed 120 projecting beyond the shoulder 25 at the rear edge of the plate 16. The plaits made in sewing the upholstering material to the backing must be of equal size, and it is the combination of the groove 25 with the plate 125 16 and lid 12 which produces this result in the following manner.

130 Assuming that the first piping seam 24 has been formed whereby the upholstery velour 23 has been folded back upon itself as illus-

trated in Figure 4 and stitched to the backing 22 at 24, the operator then places this piping seam in the groove 25 beneath the tongue 26 of the plate 16. The lid 12 is in raised position as illustrated in dotted lines in Figure 2, to facilitate this operation. The upholstery velour 23 is then passed from the groove 25 around the tongue 26 and over the top of the plate 16 up to the guide 20. The operator then presses the upholstery velour down on to the plate 16 by dropping the lid 12 downwardly thereupon. The upholstery velour is thereby held flat between the lid 12 and the top of the plate 16 although slidable therebetween. The upholstery velour 23 is then folded back over the front edge of the plate 12 as illustrated in Figure 4. The backing muslin 22 extends across the top of the table from the piping seam 24 under the plate 16. The distance from the inner edge of the groove 25 around the tongue 26 to the front edge of the lid 12 will constitute the required length of the upholstery velour necessary to make the proper size plaits for forming the pocket. The backing material 22, it will be noted, remains flat upon the top of the table and is therefore of a proportionately shorter length between the piping seam 24 and the point where the next seam will be stitched by the needle 10 and this distance is the length of the straight line along the top of the table 7 from the groove 25 to the point at which the needle 10 will form the next piping seam. The distance between the front edge of the lid 12 and the groove 25 around the tongue 26 of the plate 16 will be of any predetermined greater length than the backing strip and thus the width of the plait is determined. As the material is stitched it will be fed toward the needle 10 in a line exactly parallel to the groove 25 within which the piping seam 24 will slide and also the edge of the tongue 26, front edge of the lid 12 and the guiding member 20. A second piping seam will thus be formed exactly parallel to the one first formed and as each new plait is formed they will all be of equal size and width. The material is stitched together as is illustrated in Figure 3, with the top velour folded back upon itself and the stitch thus extending through two thicknesses of velour and one of the muslin backing. The offset portion 14 of the lid 12 assists in retaining the material in position when the lid is down as shown in Figure 4, by enclosing the seam 24 of the work slidably within the groove 25 of the plate 16. The use of the device of my invention eliminates the formerly required step of marking the material. No patterns need be outlined upon the surface of the backing material or the back of the upholstery finishing strip and the work is fed to the sewing

machine needle in exact alignment therewith so that the seams will always be exactly parallel and due to the mechanical guide for folding and retaining the material in position as it is stitched, the plaits will always be of equal size and perfectly formed. As each plait is formed the operator will raise the lid 12, slide the material rearwardly under the cross bar 11, position the newly formed piping seam 24 under the tongue 26 and within the groove 25 and again drop the lid 12 to slidably clamp the material in position whereupon the next seam may be quickly and readily formed.

Formal changes may be made in the specific embodiment of the invention described without departing from the spirit and substances of the broad invention, the scope of which is commensurate with the appended claims.

I claim:

1. In a plait forming and work guiding device adapted for use with sewing machines, the combination of a guide plate, a seam receiving groove extending along one side edge of the plate, and a hinged lid associated with said plate and positioned thereover, the forward edge of said lid being parallel to the seam receiving groove of the guide plate.

2. In a plait forming and work guiding device adapted for use with sewing machines, the combination of a guide plate, a seam receiving groove extending along the lower rear edge of said guide plate, and a hinged lid extending over said plate and associated therewith to enclose a portion of the work between the plate and lid, said lid having an offset portion adapted to be associated with the seam receiving groove of the guide plate to enclose the seam of the work therein.

3. In a plait forming and work guiding device adapted for use with sewing machines, the combination of a guide plate, a seam receiving groove extending along the lower rear edge of said guide plate, and a hinged lid extending over said plate and associated therewith to enclose a portion of the work between the plate and lid, said lid having an offset portion adapted to be associated with the seam receiving groove of the guide plate to enclose the seam of the work therein, the forward edge of said lid being parallel to said groove.

4. In a plait forming and work guiding device adapted to be associated with a sewing machine the combination of a guide plate, a seam receiving groove in said plate, a lid associated with said plate one edge of which is parallel to the groove of the plate, and a guide member on said plate extending parallel to said lid and in close proximity thereto.

5. In a plait forming and work guiding

- device adapted to be associated with a sewing machine the combination of a guide plate, a seam receiving groove in said plate, a lid associated with said plate one edge of which is parallel to the groove of the plate, said lid also having an offset portion disposed in cooperating relation with the seam receiving groove of the plate, and a guide member on said plate extending parallel to said lid and in close proximity thereto.
6. In a plait forming and work guiding device adapted to be associated with a sewing machine in stitching upholstering cover material to a backing piece in plaits, a work table, a guide plate, means to support said plate over the top of said table in spaced relation thereto, a seam receiving groove in the lower edge of said plate, the backing piece of material being receivable between the table top and guide plate and the cover material receivable over the top of the plate with the seam between the backing and covering receivable in said groove, and a lid adapted to lie over the top of the guide plate in spaced relation thereto to allow sliding of the covering material, the front edge of said lid being parallel to the groove in the plate.
7. In a plait forming and work guiding device adapted to be associated with a sewing machine in stitching upholstering cover material to a backing piece in plaits, a work table, a guide plate, means to support said plate over the top of said table in spaced relation thereto, a seam receiving groove in the lower edge of said plate, the backing piece of material being receivable between the table top and guide plate and the cover material receivable over the top of the plate with the seam between the backing and covering receivable in said groove, and a lid cooperatively hinged to said guide plate to enclose and maintain the covering material in position throughout the stitching operation.
8. In a guide device adapted for use with a sewing machine having a work supporting table, an elongated guide plate horizontally disposed over said table and spaced therefrom, a seam receiving groove extending along one edge of said plate, a guide member carried by said plate parallel to said seam receiving groove, and a hinged lid supported above the work table and guide plate in spaced relation therefrom and said hinged lid being rotatable to a horizontal position superposed above said guide plate, said lid

having a projection extending along its hinged edge parallel to the groove of the plate.

9. A work guide adapted for use with a sewing machine in stitching upholstery cover material to a backing strip in plaits including a member disposed between the covering and backing materials and a lid hinged to said member adapted to be closed over said member to slidably retain a portion of the work in position during the stitching operation. 70 75

10. A work guide adapted for use with a sewing machine in stitching upholstery cover material to a backing strip in plaits by a piping seam, including a member disposed between the covering and backing materials, a groove along one edge of said member for receiving the piping seam and a lid adapted to be closed over said member to slidably retain a portion of the work in position during the stitching operation, the edge of said lid being parallel to the seam receiving groove. 80 85

11. A work guide adapted for use with a sewing machine in stitching upholstery cover material to a backing strip in plaits by a piping seam, including a member disposed between the covering and backing materials, a groove along one edge of said member for receiving the piping seam, a lid adapted to be closed over said member to slidably retain a portion of the work in position during the stitching operation, the edge of said lid being parallel to the seam receiving groove, and a guide carried by said member, parallel to the edge of the lid and groove to insure parallel seams. 90 95

12. In a plait forming and work guiding device adapted for use with a sewing machine for sewing a material to be plaited to a backing material, means for determining the width of the plaits to be formed, including a member adapted to be disposed between the material to be plaited and the backing material and a lid adapted to be disposed over said member to retain the material in proper relation thereto during the sewing operation. 100 105 110

13. A work guide adapted for use with a sewing machine in stitching upholstery cover material to a backing strip in plaits, including a member disposed between the covering and backing materials and a lid adapted to be closed over said member to slidably retain a portion of the work in position during the stitching operation. 115 120

CECIL E. BOYD.
